UNITED STATES PATENT OFFICE.

JAMES E. GILMORE, OF PRINCE RUPERT, BRITISH COLUMBIA, CANADA.

OAKUM SEAM-CALKING TOOL.

1,296,948.

Specification of Letters Patent. Patented Mar. 11, 1919.

Application filed July 3, 1917. Serial No. 178,450.

To all whom it may concern:

Be it known that I, JAMES E. GILMORE, a citizen of the Dominion of Canada, residing at Prince Rupert, in the Province of British Columbia, Canada, have invented certain new and useful Improvements in Oakum Seam-Calking Tools, of which the following is a specification.

This invention relates to a tool for calking the seams of any ship or craft where wood is used for hull or deck, the tool being adapted for use with a pneumatic or any power-operated hammer. In calking such seams with the tool commonly used for such purpose the tool penetrates the seam to such a depth that the operator cannot disengage it to move it along the seam while it is exposed to the percussive action of a pneumatic or other power hammer.

This difficulty I overcome by using a rotatable calking disk, the edge of which is in cross section shaped to the form of the various calking tools used. A pair of these disks are mounted tandem-wise in a frame having a percussive head on which the blows of a power hammer may be delivered, so that the tool may be moved along the seam while it is being struck by the hammer.

Provision is also made by which the axis of the percussive head may be endwise moved on the frame that a greater impact may be delivered more directly to one wheel or the other where the greatest calking resistance is experienced.

There are several other features of importance to the satisfactory working of the device to which attention is drawn in the following specification, reference being made to the drawings by which it is accompanied, in which:

Figure 1 is a side elevation of the device.

Fig. 2, a plan of the same.

Fig. 3, a vertical section on the line 3—3 in Fig. 1.

Fig. 4, a vertical section on the line 4—4 in Fig. 1.

Fig. 5 is a cross section of the frame showing the pin connection of the guide fences thereto, and

Fig. 6 is a plan of the guide fences in front of one calking wheel.

The device comprises a pair of steel disks

2 and 3, the edges of which are in cross section shaped to the requirement of use in layering and calking the oakum or other calking material into a seam. These calking wheels 2 and 3 are rotatably mounted tandem-wise in a frame 4 in a manner that they are readily removable to enable wheels of different cross section to be used as required.

Secured to the upper side of this frame 4 midway between the wheels 2 and 3 is a percussive stem 6, the attachment being such as will permit a limited longitudinal movement of the stem on the frame to permit the axis of it to be moved nearer to one or other of the axles 5 of the wheels 2 or 3 as required. The percussive head is here shown as divided in the plane of the calking wheels to straddle them and have a well distributed bearing on the frame 4 on each side and is secured by a bolt 7 through an elongated slot 8 in a downward extension from each side of the percussive head bearing on the frame 4. This bolt connects the percussive head to the frame and secures it in any desired position of adjustment thereon.

The stem of the percussive head has a handle sleeve 9 mounted on it by which the device may be held in the hand of the user without receiving the shock of the blow. On this handle provision for controlling the power hammer may be mounted, but such is not material to the subject matter of this application. Another handle 10 is pivotally mounted on a pin 11 at the back end of the frame 4 in a manner that by tightening the bolt or pin the handle may be secured in any position of angular adjustment to suit the convenience of the user.

To retain the calking material in the plane of the seam where it will be engaged by the calking wheels a pair of guide fences 12 downwardly project from the underside of the frame 4 in advance of each of the calking wheels 2 and 3, each fence being independently connected to the frame 4 by pins 13 upwardly projecting from the fence and vertically movable in the sides of the frame. The heads of these pins 13 are on the upper side of the frame 4 and the fences are normally held at the lower limit of

their movement by a spring 14 coiled on each pin between the fence and the underside of the frame.

The leading ends of these guides are outwardly flared from the line of the seam, as shown in Fig. 6, to collect and retain the calking material in the line of the seam where it will be engaged by the calking wheels.

10 The holes in which the pins 13 are endwise movable in the frame 4 are laterally enlarged outward toward the underside, as shown in Fig. 5, to permit the fences a certain amount of lateral movement outward 15 against the resistance of their springs, which tend to hold them toward the line of the seam.

To guide the calking disks in the seam being calked, seams 15 are removably attached to project at right angles from each 20 end of the frame on either side. A spare calking wheel 17 is mounted on the end of each stem between collars 16 which are adjustable on the stem that the guide wheels 25 may be set to the distance of the seams apart.

In use, the calking wheels 2 and 3 are applied to the seam to be calked with the guide wheels 17 in the next open seam, and the 30 percussive hammer being applied to the end of the stem 6, as the blows are delivered the tool is rolled along the seam. The spring-controlled fences 12 bear on the faces of the planks and while permitting the calking 35 wheels to penetrate the seam resiliently guide the oakum or other calking material into the plane of the wheels. As the tool is advanced along the seam provision may be made between the wheels 2 and 3 or in front of each 40 of them for applying oil or grease to the edges of the calking wheels to prevent them binding in the seams.

The device constitutes a convenient tool enabling the modern pneumatic or other 45 power hammer to be applied to calk the seams of wooden-built vessels, or the wooden decks of steel ships.

I do not desire to be confined to the particular construction here set forth as the 50 same may be modified within the scope of the following claims which set forth what I desire the protection of Letters Patent on.

1. A tool for calking the seams between the boards of the hull or the deck of a vessel, 55 said tool comprising a disk, a frame in which said disk is rotatably mounted, a stem shiftably connected to said frame, whereby the position of said stem along said frame may be changed to vary the force of impact with 60 relation to the axis of the disk.

2. A tool of the class described, comprising a pair of disk wheels rotatably mounted tandem-wise in a frame and a stem connected to the frame and adjustable on it between the 65 axles of the disks.

3. A tool of the class described, said tool comprising in combination, a pair of wheels rotatably mounted tandem-wise in a frame, the edges of which wheels are in cross section shaped to effect the layering and calking 70 of a seam, a stem member adapted to receive the blows of a power hammer secured on the upper side of the frame to be adjustable between the axles of the wheels, and means downwardly projecting from the frame on each side of each wheel for resiliently retaining the calking material in the plane of the wheels.

4. A tool of the class described, said tool comprising in combination, a pair of disk 80 wheels rotatably mounted tandem-wise in a frame, the edges of which disks are in cross section shaped to effect the layering and calking of the seams, a stem member secured on the upper side of the frame to be adjustable 85 between the axles of the wheels, said member adapted to receive the blows of a power hammer, and a guide fence mounted on each side of each wheel, said fence resiliently yielding toward the frame and outward from 90 the line of the seam.

5. A tool of the class described, said tool comprising in combination, a pair of disk wheels rotatably mounted tandem-wise in a frame, a stem member secured to the upper 95 side of the frame to be adjustable between the axles of the wheels, a guide fence downwardly projecting from the underside of the frame on each side of each disk wheel, springs resisting upward movement of each fence toward the frame and outward movement of the fence from the plane of the disk wheels, provision for holding said tool to its work, and means for guiding the tool from a parallel seam.

6. A tool of the class described, said tool comprising in combination a pair of disk wheels rotatably mounted tandem-wise in a frame, a stem member secured on the upper side of the frame to be adjustable between 110 the axles of the wheel, a guide fence downwardly projecting from the frame on each side of each disk wheel, springs interposed between the fence and the frame normally holding the fence at the lower limit of its 115 movement, and a handle by which the tool may be applied to its work.

7. A tool of the class described, said tool comprising in combination a pair of disk wheels rotatably mounted tandem-wise in a 120 frame, a stem member straddling the wheels and secured to each side of the frame between the wheel axles, said stem member adapted to receive the blows of a power hammer, a fence below the frame on each side 125 of each wheel, said fence having pins upwardly projecting from it to pass through apertures in the frame, springs holding said fences at the lower limit of their movement and toward the middle line, a handle pivot- 130

ally connected to the end of the frame to be angularly adjustable in relation thereto, and a handle sleeve on the stem.

8. A tool of the class described, comprising a plurality of disk wheels, a frame, axles for said wheels rigidly mounted in said frame, a single impact receiving device con-

nected to said frame, and means whereby the place of connection of said device with said frame may be shifted to vary the impacting effect with relation to the several disk wheels. 10

In testimony whereof I affix my signature.

JAMES E. GILMORE.
